MICHAEL LOCK, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

VOLTAGE REGULATOR.

Application filed January 7, 1925, Serial No. 938, and in Germany January 14, 1924.

The invention relates to a voltage regulator, particularly used for regulating the filament voltage of wireless arrangements of aeroplanes, the heating current generators 5 of which are driven by the propeller.

An object of the invention is to provide a voltage regulator which is responsive to change in speed of the generator and which will keep the voltage of the generator substantially constant irrespective of the speed 10 of the generator. This invention while applicable to regulating the voltage of generators, is particularly applicable to use on airships where the generator for supplying the filament current of thermionic tubes of a radio set is driven by a propeller.

This and other objects will be apparent from the following description and claims when considered with the accompanying 20 drawing in which the single figure is a dia-grammatic representation of the invention.

The principle of the invention is, that the speed variations of the propeller effect a centrifugal governor by which the voltage variations which are caused by the speed variations are compensated. An appropriate embodiment of the invention is obtained by having one or more springs arranged on a disc which is driven by the propeller, these 25 springs being influenced by the centrifugal force at a certain speed, so that they effect contact devices which act upon the excitation of the generator producing the filament current. The voltage regulation is then carried out by producing a countermagnetization in the exciting windings of the filament current generator at increasing speed, causing an increase of voltage, and by short-circuiting a resistance in the exciting wind- 30 ings at decreasing speed.

Referring to the drawing for a more detailed description of the preferred arrangement, S is the disc driven by and rotating together with the propeller (not shown).

On this disc one end of spring F is secured, the other end working between two contact points K₁ and K₂ also fixed to the disc S. G is the filament current generator also driven by the propeller. At increasing speed 45 the spring F is brought into contact with K₁, whereby a counter-winding M is inserted into the excitation of the generator and consequently the voltage is decreased. If the speed decreases, the spring F is not 50 only disconnected from contact point K₁,

thereby cutting out the counter-winding M, but it is brought into contact with contact point K₂ and the resistance W short-circuited, the voltage through the field windings f thus increased, and the voltage again 60 increased. If the speed now increases, the spring F will be disconnected from contact K₂, cutting in resistance W and also will make contact with contact point K₁.

Thus this cycle of events will continue so 65 long as the speed of generator G varies and the voltage will be kept substantially constant in spite of these variations.

Having described one embodiment of my invention, I am entitled to all modifications thereof as fall fairly within the scope 70 of the following claims.

I claim:

1. In a regulating system, a generator, a main field winding and an oppositely wound 75 auxiliary field winding, a resistance in series with the main field winding, a regulator comprising a centrifugally actuated body and contact members associated therewith for cutting in and out both the resistance and said auxiliary winding upon changes in 80 the speed of rotation of said generator.

2. In a regulating system the combination of a generator, a pair of elements associated with the field circuit of the generator 85 to vary the field strength in like manner when both are rendered operative and a member centrifugally actuated in accordance with the generator speed adapted to render said pair of elements operative. 90

3. In a regulating system a generator, a controlling winding operative for varying the field of said generator, a resistance for varying the field current, a regulator comprising a body centrifugally actuated in accordance with the speed of the generator and having contact members associated therewith for simultaneously cutting said field resistance in and out of the field circuit and rendering said controlling winding respectively operative and inoperative. 95

4. A regulating system; comprising a generator having two oppositely acting exciting field windings, a resistance in series with one of said windings, a centrifugal regulator device mounted on and turning with the shaft of said generator, and having contact means for cutting in and out said resistance and one of said windings upon changes in the speed of rotation of said generator shaft. 105 110

5. A regulating system, comprising a generator having a field winding, a resistance in said field winding, a second field winding acting in opposition to said first named 5 winding, and means comprising a centrifugally operated device for eliminating said resistance and said oppositely acting winding at certain speeds of said generator and bringing said resistance and said oppositely 10 acting winding into operation at certain other speeds of said generator for controlling the field thereof.
6. A regulating system, comprising a generator having two oppositely acting field 15 windings, a resistance in series with one of said windings, a regulator comprising a centrifugally actuated body, contact members actuated by opposite movements thereof, means controlled by one of said contacts 20 and said centrifugally actuated body for short circuiting said resistance at low speeds of said generator and means controlled by said other contact and said centrifugally ac-
- tuated body for effecting a counter-magnetizing action on said generator field at high 25 speeds of said generator.
7. In a regulating system, a generator having two oppositely acting field windings, a resistance in series with one of said windings, a regulating device mounted on the 30 shaft of said generator, a centrifugally actuated vibrating arm on said device, two contacts also on said device and disposed one on each side of said vibrating arm, whereby said vibrating arm may contact with one of said contacts at certain speeds 35 of said shaft and with the other of said contacts at certain other speeds of said shaft, connections between said contacts, said vibrating arm, said resistance and one of said field windings, whereby said resistance and said last named winding are cut in and out according to the speed of said shaft 40 to control the voltage of said generator.
